US00D940493S

(12) **United States Design Patent** (10) **Patent No.:** **US D940,493 S**
(45) **Date of Patent:** **** Jan. 11, 2022**

(54) **LIQUID STORAGE DEVICE**

(71) Applicant: **INTRADIN (SHANGHAI) MACHINERY CO., LTD.**, Shanghai (CN)

(72) Inventor: **Xuetao Qiao**, Shanghai (CN)

(73) Assignee: **INTRADIN (SHANGHAI) MACHINERY CO., LTD.**, Shanghai (CN)

(**) Term: **15 Years**

(21) Appl. No.: **29/706,884**

(22) Filed: **Sep. 24, 2019**

(51) LOC (13) Cl. **09-02**

(52) U.S. Cl.

USPC **D7/313; D34/39**

(58) **Field of Classification Search**

CLAIM

(57) The ornamental design for a liquid storage device, as shown and described.

DESCRIPTION

FIG. 1 is a perspective view of a liquid storage device showing my new design;

FIG. 2 is a front elevation view thereof;

FIG. 3 is a back elevation view thereof;

FIG. 4 is a left side view thereof;

FIG. 5 is a right side view thereof;

FIG. 6 is a top plan view thereof; and,

FIG. 7 is a bottom plan view thereof.

The broken lines in the drawing depict environmental subject matter only and form no part of the claimed design.
